UNITED STATES PATENT OFFICE.

JOHN W. SMITH AND ELMER H. SMITH, OF MINNEAPOLIS, MINNESOTA.

ACETYLENE-BLOWPIPE.

1,152,985.

Specification of Letters Patent.

Patented Sept. 7, 1915.

Application filed June 16, 1913. Serial No. 773,979.

To all whom it may concern:

Be it known that we, JOHN W. SMITH and ELMER H. SMITH, citizens of the United States, residents of Minneapolis, county of 5 Hennepin, State of Minnesota, have invented certain new and useful Improvements in Acetylene-Blowpipes, of which the following is a specification.

In the use of a blow pipe of this type for 10 cutting metal, it is customary after heating the metal with the acetylene burner to apply a stream of oxygen for cutting the metal. It has been found difficult to move the blow pipe or torch at a suitable speed 15 over the metal and a speed that may be varied according to the thickness of the metal to be cut.

The object of our invention is to provide a 20 device for moving the blow pipe through the pressure of the oxygen, the speed of movement being regulated according to the thickness of the metal over which the pipe is moving.

Our invention consists generally in various 25 construction and combinations, all as hereinafter described and particularly pointed out in the claims.

In the accompanying drawings forming 30 part of this specification, Figure 1 is a side view, partially in section, of an acetylene blow pipe embodying our invention, Fig. 2 is a plan view of the same, partially in section, Fig. 3 is a transverse sectional view on line $x-x$ of Fig. 1, showing the means for 35 operating the feed mechanism of the torch by the pressure of the oxygen.

In the drawing, 2 represents the handle of 40 the blow pipe, having the acetylene supply pipe 3 and oxygen supply pipe 4. These pipes we have shown broken away in Fig. 1 to illustrate more clearly the pure oxygen supply pipe by means of which oxygen in any suitable pressure is supplied to the nozzle when it is desired to cut through the 45 metal.

5 represents the pure oxygen supply pipe and 6 a valve inserted therein having an operating lever 7 within convenient reach of the handle 2.

50 8 is a casing, preferably of metal, having a cover 9 provided with a gas-tight joint 10. This casing has supporting wheels 11 mounted on a shaft 12 which has bearings in the walls of the casing and provided with gas tight joints 13. A gear wheel 14 is mounted 55 on the shaft 12 and meshes with a pinion 15

on a shaft 16 which supports a gear wheel 17. A pinion 18, mounted on a shaft 19, meshes with the gear 17. A worm wheel 20 is mounted on the shaft 19 and is driven from a worm 21 on which a fan 22 is mounted. The pure oxygen pipe has tubes 23 and 24 leading therefrom and provided with nozzles which project through the wall of the casing in position to direct the gas under 60 pressure upon the blades of the fan above and below its axis. A regulating valve 25 is provided and by means of this valve and the valve 6 the operator can vary the volume of gas discharged against the blades of the 65 fan and thereby regulate its speed of revolution.

Evidently, if all the gas is allowed to flow 70 through the tube 23 against the fan while the flow of gas through the tube 24 is cut off, the fan will be revolved at a high speed. On the other hand, if a portion of the gas is admitted through the tube 24 it will act as a 75 brake or a retarding means for the fan, reducing its speed, and by the adjustment of the valve 25 the operator of the blow pipe can easily regulate the flow of gas to the fan 80 and thus control the travel of the blow pipe over the metal, according to the thickness of the metal to be cut. If the metal is com- 85 paratively thick, it will be desirable to move the torch at a slower speed, while if the cutting is to be done through a comparatively thin plate, then the torch may be operated at a higher speed, and all this may be accomplished by the feed of the gas to the fan 90 through which the supporting wheels are revolved.

The casing 8 will, of course, be made gas 95 tight and at one end is provided with a port 26 leading to a pipe 27 which communicates with the cutting nozzle 28, these nozzles being varied according to the character of the cut and thickness of the metal.

We claim as our invention:-

1. The combination, with an acetylene blow pipe and a carrier therefor, of an oxygen supply pipe and mechanism actuated by the pressure of the oxygen for operating said carrier to move said blow pipe. 100

2. The combination, with a blow pipe and a carrier therefor, of a pipe for supplying gas under pressure, and mechanism actuated by the pressure of the gas for operating said carrier to move said blow pipe. 105

3. The combination, with an acetylene blow pipe and nozzle therefor, of a carrier

- supporting said pipe, and comprising a closed casing and supporting wheels therefor, mechanism within said casing having driving connections with said wheels, an oxygen supply pipe having pipe connections with said casing, said mechanism including means actuated by the pressure of the oxygen for operating said wheels, and a nozzle having a pipe connection with said casing.
- 13 4. The combination, with an acetylene blow pipe, of a wheeled carrier therefor and including a casing, a fan mounted therein having a driving connection with the wheels of said carrier, an oxygen supply pipe having tubes leading through said casing for directing the oxygen against the blades of said fan, above and below its axis, regulating valves for said tubes, and a nozzle having a pipe connection with said casing.
- 15 5. An acetylene blow pipe comprising a handle, acetylene and oxygen gas supply pipes and a nozzle therefor, a pure oxygen supply pipe and a regulating valve therefor, and means supporting said blow pipe and actuated by the pressure of the oxygen for moving said blow pipe back and forth over the metal to be cut.
- 17 6. A self-contained, mechanically propelled gas cutting apparatus, portable and adapted to travel in any desired direction on an underlying surface, the same comprising a carriage mounted on driving wheels and

having a nozzle, and a gas-propelled mechanism connected with said wheels for moving said carriage and nozzle.

35

7. A gas cutting apparatus comprising a carriage having supporting wheels and a nozzle, and a driving mechanism connected with said wheels and actuated by a gas under pressure for operating said carriage.

40

8. The combination, with a wheeled traveling member and a jet delivering means, of a gas propelled motor carried by said member and geared to a wheel thereof to drive the same, and means whereby the gas pressure is utilized to retard the speed of the motor.

45

9. The combination, with a blow pipe, of a wheeled carrier therefor, a vane mounted therein and having a driving connection with the wheels of the carrier, a gas supply pipe having tubes for directing the gas against the blades of said vane above and below its axis, regulating valves for said tubes, and a nozzle having a pipe connection with said carrier.

50

In witness whereof, we have hereunto set our hands this 12th day of June 1913.

JOHN W. SMITH.
ELMER H. SMITH.
